HANDLE FOR CASKETS, ETC.

Albert A. Sidi, Brooklyn, N. Y., assignor to New York & Brooklyn Casket Co., Brooklyn, N. Y., a corporation of New York

Application August 5, 1942, Serial No. 453,621

7 Claims. (Cl. 16—112)

This invention relates generally to handles and more particularly to handles for burial caskets and the mounting thereof.

It is an object of my invention to produce a handle for a casket that is hingedly mounted so that when not in use it may hang down alongside the wall of the casket.

Another object is to limit the outward swinging movement of the handle.

Still another object is to relieve the hinge portion of the handle from a portion of the stress in lifting the casket.

A further object is to conceal the stress relieving and movement limiting means and thereby make the handle more compact and pleasing in appearance.

Yet another object is to provide a handle with such stress relieving and movement limiting means having a minimum of metal parts.

Another object is to provide a hinged casket handle with means in common for limiting the movement of said handle, for relieving the stress from the handle and for concealing said limiting and relieving means.

Another object is to provide a wooden hinged handle of this type that is economical to manufacture.

In the drawing,

Fig. 1 is a vertical sectional view showing a wall of a casket on which is mounted one form of my improved handle.

Fig. 2 is a sectional view taken on the plane of the line 2—2 of Fig. 1 and looking in the direction of the arrows.

Fig. 3 is a front view of the handle.

The casket is provided with a number of hinged handles 5 for supporting a hand rail 6 along its wall 7 for lifting and carrying the casket.

Each handle comprises a block having an inner flat surface 8 and a suitably designed outer surface 9. The handle is connected to the wall 7 by a hinge 10, the hinge pin 11 being positioned adjacent the upper edge thereof. The lower portion is somewhat enlarged and provided with an opening 12 for receiving the hand rail.

The hinge 10 has two leaves 13 and 14, one of which 13 is suitably secured to the flat inner surface 8 of the handle as by screws 15, 15, and the other leaf 14 is secured to the outer casket wall. The anchor bolt 16 is preferably secured in place by two nuts 17 and 18 and may also serve to secure the hinge leaf 14 to the casket wall.

The hinge leaf 13 on the handle has an elongated slot 19 adjacent its central portion. Each

5 handle 5 is formed with a recess 20 in its upper portion, just behind and in alignment with the slot 19. The hinge leaf 13 serves as a closure plate for this recess 20.

10 The bolt 16 extends laterally and freely through the slot 19 into the recess 20. Its free end in the recess has a head portion 21 larger than the slot 19 to limit the outward swinging movement of the handle. This bolt together with the nuts 17 and 18 serves as the means for fastening the hinge to the casket wall and also with its headed portion serves to limit the outward swinging movement of the handle. It also serves to relieve the hinge pin of stress when the casket is lifted. The leaf 13 in addition to mounting the handle 5, and to limiting the outward movement of the handle also conceals the recess 20 and the bolt head 21.

15 By adjusting the bolt 16 inwardly or outwardly of the wall, the distance the handle can swing outwardly may readily be varied, and by affording a recess in the handle for the end of the bolt, the handle is permitted to fall down close to the side of the casing wall when not in use.

20 The inclined shoulder at the back of the head of the bolt provides a convenient abutment surface for engagement by the outer leaf of the hinge when the handle is raised so that the strains are better distributed.

25 30 It will be noted that the handle may be made as an article of manufacture to be supplied to casket manufacturers and that it permits a wide scope in the design and material of handle employed, since the handle mounting is entirely concealed behind the handle.

I claim:

1. In a casket, a handle member having a body 35 with a recess, a hinge connection between the handle and side wall of the casket including two hinge leaves, an elongated member passing through the wall of the casket and extending laterally and exteriorly thereof, through one leaf of the hinge and through the other leaf and extending into the handle recess and having an enlarged head within said recess for limiting the outward swinging movement of the handle.

2. In a casket, a wooden handle having a body portion hingedly mounted thereon and means in common for limiting the movement of the handle, for taking part of the stress off the handle and for concealing said limiting and relieving means including a recess in one surface of said body portion, a stationary rigid bolt passing through one wall of the casket and extending into said recess and a closure plate for said recess in sliding

engagement with said bolt, said bolt having an enlarged head within said recess.

3. In a casket, a wooden handle hingedly mounted thereon and means for limiting the movement of the handle including a recess in one surface of said handle, a stationary rigid bolt passing through one wall of the casket and extending into said recess, an enlargement on the end of the bolt in the recess and a closure plate for the recess adapted to be engaged by said enlargement for limiting the movement of the handle.

4. A handle with means for hinging it to a casket wall, comprising a body portion having a recess in one surface thereof, a hinge having one leaf secured to the body portion over said recess, said hinge having a slot aligned with said recess, the other being adapted to be secured to a casket wall and a stationary anchor bolt secured to the latter leaf and extending through said slot into said recess and having an enlarged head in said recess adapted to limit the relative movement of the hinge leaves.

5. In a casket a wall having an opening therethrough, a handle having a body portion with a recess in one surface thereof, a hinge connection between said wall and handle including a pair of hinge plates, one of said hinge plates being fastened to the body portion over said recess and being provided with a slot communicating with said recess, the other of said hinge plates being fastened to the wall and being formed with an opening and a stationary bolt passing through the openings in said wall and hinge plate and through said slot and extending into said recess, and an enlargement on said bolt in said recess adapted to engage the walls of said slot for limiting the swinging movement of the handle and for relieving the strain on the hinge pivot.

6. In a casket, a wall having an opening therethrough, a handle having a body portion with a recess in one surface thereof, a hinge connection between said wall and handle including a pair of hinge plates, one of said hinge plates being fastened to the body portion over the recess and being provided with a slot communicating with said recess, the other of said hinge plates being mounted on the wall and being provided with an opening and an adjustable bolt passing through the openings in said wall and hinge plate and protruding exteriorly thereof through said slot into the recess, an enlargement on said bolt in said recess for engaging the walls of the slot and common means on the bolt for adjusting the length of its protruding portion and for clamping the last named hinge plate to the wall.

7. In a casket, a wall having an opening, a handle having a body portion with a recess in one surface thereof, a hinge connection between said wall and handle including a hinge plate fastened to one side of the wall and provided with an opening and another hinge plate fastened to the recessed surface of the handle body portion and closing said recess and provided with a slot communicating with said recess, a stationary bolt member passing through the openings in said wall and hinge plate and extending exteriorly thereof and through said slot into said recess, one end of said bolt being fastened to the inner side of the wall and the other end of the bolt having a head portion in the recess larger than the slot and adapted to engage the wall portion of said slot whereby swinging movement of the handle is limited and the strain on the hinge pivot is relieved.

ALBERT A. SIDI.
